(57) **CLAIM**

The ornamental design for a TV with player, as shown and described.

DESCRIPTION

FIG. 1 is a front elevational view of a first embodiment of a TV with player showing our new design;

FIG. 2 is a side elevational view thereof, the other side being a mirror image thereof;

FIG. 3 is a top plan view thereof;

FIG. 4 is a back elevational plan view thereof;

FIG. 5 is a bottom plan view thereof; and,

FIG. 6 is a front elevational view of a second embodiment thereof, all other views of the second embodiment being identical to the corresponding views of the first embodiment.
